UNITED STATES PATENT OFFICE.

BERT HUMPHREY, OF COAL RUN, OHIO.

REGULATOR FOR WATER-HEATING SYSTEMS.

No. 893,503.

Specification of Letters Patent.

Patented July 14, 1908.

Application filed April 28, 1908. Serial No. 429,642.

To all whom it may concern:

Be it known that I, BERT HUMPHREY, a citizen of the United States, residing at Coal Run, in the county of Washington and State 5 of Ohio, have invented a new and useful Regulator for Water-Heating Systems, of which the following is a specification.

This invention relates to water heating systems and has a special reference to regulators 10 for the same.

One object of the invention is to provide an improved mercury seal regulator for water heating systems wherein the expanding wa- 15 ter will be forced through the mercury seal but the contracting water allowed free pas- sage and not to be required to pass through said seal.

Another object of the invention is to pro- 20 vide an improved means for maintaining the water level at substantially uniform height so that the pressure throughout the system is maintained substantially uniform.

The invention consists primarily in a trap 25 having a mercury seal and an automatic valve arranged to close when the water is ex- panded and open when the water is con- tracted, together with a means for auto- matically supplying water to the system to maintain a substantially uniform level.

30 The invention further consists in such novel arrangement of details and combina- tions of parts hereinafter fully set forth, illustrated in the accompanying drawings, and specifically claimed.

35 In the accompanying drawing the figure is a vertical section through a regulator con- structed in accordance with this invention.

The invention consists of an outer casing 10 wherein is mounted an inner chamber 11, 40 the same being held in spaced relation to the walls of the outer casing. Communication is afforded between the inner chamber and the outer casing at the bottom and preferably by means of a plurality of openings 12 45 in the bottom of the chamber 11. An inlet pipe 13 is connected to the heating system 10 and extends through the outer casing and into the inner chamber. An outlet passage 14 is formed at the upper end of the chamber 11 and is a second means of communication 50 between the inner chamber and the chamber formed by the outer casing. A valve seat 15 is formed within the chamber 11 at the inner end of the pipe 14. A hollow ball 16 is held 55 within the casing 11 and is adapted to rise and close the passage 14 when the casing 11

becomes filled with water. Mercury is held at the lower portion of the device as indicated at 17 to form a seal between the inner chamber and the chamber formed by the 60 outer casing.

The upper end of the casing 10 is provided with an outlet pipe 18 which leads to an ex- pansion chamber 19. A cold water supply pipe 20 is connected to any suitable source of 65 cold water supply and is provided with a ball valve 21 arranged to open when the water level lowers beyond a certain point and close when it rises above that point. An over- 70 flow connection 22 is formed at the upper end of the expansion chamber and may be connected to a waste pipe not deemed necessary here to be shown.

At the upper end of the inlet pipe 13 is formed a screen 23 which not only prevents 75 refuse of any sort finding its way into the hot water heating system, but also prevents the ball 16 from sealing the end of the pipe 13 under conditions in which the water level is sufficiently low to permit the ball to rest 80 thereon.

In the operation of the device let it be as- sumed that the system is cold and the water level is that indicated in the drawing. As 85 the water is heated the expansion will force the water into the chamber 11 and will thus displace the mercury in that chamber. As the water continues to expand it passes out of the openings 12 and bubbles up through the mercury into the chamber formed by the 90 outer casing. This will, of course, raise the water level in the expansion chamber 19 but inasmuch as this device occupies a relatively small portion of the height of any system to which it is intended to be attached, the 95 change in level in the system will not be suffi- ciently great to substantially affect the pres- sure in the system. If the water expands suffi- 100 ciently it will flow out of the pipe 22 and into the waste pipe. Suppose now that the water is cooling off and contracting. The first 105 effect that this will have will be to restore the mercury seal to a common level both in and out of the chamber 11. Next, the mercury seal outside of the chamber will be depressed somewhat until such a time as the ball 16 is slightly freed from the seat 15. The water will then pass down through the passage 14 and chamber 11 into the pipe 13. Mean- 110 while the water level in the expansion cham- ber 19 will be lowered and if the contraction is continued sufficiently long, the valve 21

will open and permit water to flow into the expansion chamber 19 through the pipe 20. This, at ordinary rate of contraction will serve to maintain the water level about uniform. But however, if the water contracts 5 too rapidly or runs out of the pipe 13 too quickly the water level will be lowered to a point below that of which the ball 16 will float into the valve seat 15. If this lowering 10 continues sufficiently for the ball to drop to the top of the screen 23 that screen will act to prevent the shutting off of the contracting water from the pipe 13, as is indicated with a dotted line position of the ball 16. It will 15 thus be seen that the contracting water has free passage through the opening 14 and pipe 13 while expanding water is forced through the mercury seal.

Having thus described the invention what 20 is claimed is:—

1. In a regulator for water heating systems, an outer casing, an inner chamber supported in spaced relation to said outer casing and freely communicating at the bottom 25 therewith, and provided with a valved outlet opening, a mercury seal between the bottom of said casing and chamber, an inlet pipe communicating with said inner chamber, and an outlet pipe leading from said chamber, 30 said pipe being disposed above said liquid seal.

2. In a regulator for water heating systems, an outer casing, an inner chamber supported in spaced relation to said outer casing 35 and freely communicating at the bottom therewith, and provided with an outlet opening, a valve arranged to close said outlet opening during expansion of water held in said regulator and open said outlet opening 40 during contraction of said water, a mercury seal between the bottoms of said casings and chamber, an inlet pipe communicating with said inner chamber, and an outlet pipe leading from said casing, said pipe being disposed 45 above said mercury seal.

3. In a regulator for water heating systems, an outer casing, an inner chamber supported in spaced relation to said outer casing and freely communicating at the bottom 50 therewith, and provided with an outlet open-

ing, a ball valve seat formed at the inner end of said outlet opening, a ball valve floatably mounted in said chamber and arranged to close said outlet opening during the expansion of water contained in said system and to 55 open the same during the contraction of said water, a mercury seal between the bottoms of said casing and chamber, an inlet pipe communicating with said inner chamber, and an outlet pipe leading from said casing, said 60 pipe being disposed above said liquid seal.

4. In a regulator for water heating systems, an outer casing, an inner chamber supported in spaced relation to said outer casing and freely communicating at the bottom 65 therewith, and provided with a valved outlet opening, a liquid seal between the bottoms of said casing and chamber, an inlet pipe communicating with said inner chamber provided with an end extending above said mercury seal, an outlet pipe leading from said casing above said mercury seal, and an expansion chamber connected to said outlet pipe.

5. In a regulator for water heating sys- 75 tems, an outer casing, an inner chamber supported in spaced relation to said outer casing and freely communicating at the bottom therewith, and provided with a valved outlet opening, a mercury seal between the bottoms 80 of said casing and chamber, an inlet pipe communicating with said inner chamber, provided with an end extending above said mercury seal, an outlet pipe leading from said casing above said mercury seal, an ex- 85 pansion chamber connected to said outlet pipe, a cold water supply pipe leading to said expansion chamber, and a ball valve held in said expansion chamber arranged to open said pipe when the water level is lowered be- 90 yond a predetermined point and close the same when the water level is above said point.

In testimony that I claim the foregoing as my own, I have hereto affixed my signature 95 in the presence of two witnesses.

BERT HUMPHREY.
